United States Patent Office.

WILLARD H. SABINS, OF ROCKFORD, ILLINOIS.

Letters Patent No. 86,595, dated February 2, 1869.

IMPROVEMENT IN CORN-PLANTERS.

The Schedule referred to in these Letters Patent and making part of the same.

To all whom it may concern:

Be it known that I, WILLARD H. SABINS, of Rockford, in the county of Winnebago, and State of Illinois, have invented new and useful Improvements in Seed-Planters; and I do hereby declare that the following is a full and exact description of the same, reference being had to the accompanying drawings, and to the letters of reference marked thereon.

This invention relates to certain improvements in seed-planters; and

It consists—

First, in the manner of opening the ground for the reception of the seed;

Second, in certain devices for delivering the seed; and

Third, in the manner of covering it.

Other points, of minor importance, are believed to be novel, all of which will be fully described herein-after.

In the drawings—

Figure 1 is a plan view of my invention;

Figure 2 is a side elevation;

Figure 3 is a plan view of the bottom of the hopper; and

Figure 4, a transverse section of one of the disks *e*.

To enable those skilled in the art to which my invention appertains, to make and use the same, I will now proceed to describe its construction and operation.

A represents the front bar of the machine, to which the team is attached.

B *B* represent bars extending rearwardly from the bar *A*, to which are attached the earth-openers, or plows.

C *C* represent standards, rising perpendicularly from bar *A*, to which are rigidly attached the front ends of handles *D*, which latter are also connected with bars *B*, by means of the standards *d* *d*. By this construction, it will be observed that the handles *D* and bars *A*, *B* *B*, are rigidly connected together, and form what may be called the main frame of the machine.

E *E* represent arms extending rearwardly from the upper ends of the standards *C* *C*, which are connected together at their rear ends by means of the bar *E*'.

These arms are pivoted to the standards *C* *C*, and, with the bar *E*', form an adjustable frame.

E' represents a shaft, turning in bearings in the arms *E* *E*, upon which is placed the wheel *E*''.

Upon the ends of shaft *E*'' are the disks *e* *e*, which have in their faces the seed-cups *e* *e*'. These cups are regulated to sow a greater or less quantity, by means of a screw, the head of which forms the bottom of the cup. By turning this in or out, the cup is made to hold more or less, as may be desired.

F *F* represent hoppers, located over the disks *e* *e*', which have the conducting-spouts *f* *f*, leading into the delivery-spouts *b* *b* upon the bars *B*.

Within the hoppers *F* *F* are rubber bushings, *f*', against which the disks turn. These bushings are made dovetailing in form, and are fitted into corresponding sockets in the bottom of the hopper. They also are secured in place by a metal plate, as shown.

B *B*' represent the earth-openers, which are constructed of a triangular, wedge-shaped form, being intended, not to cut open the earth, but crowd it to either side. The rear, and wider part of the opener, is cut away at the bottom, so that the seed is delivered at the rear end, the opener, in fact, forming a continuation of the delivery-spouts, so that the seed is not exposed at all after it enters the hopper.

H *H* represent the coverers, which consist of a pair of curving blades, of the shape shown, which flare outward from each other slightly at the rear ends.

I represents a scraper upon the bar *E*', by means of which the wheel is cleaned.

J *J* represent hinged markers, attached to the extreme ends of the bar *A*, by means of which the ground is laid off.

The operation of my machine is as follows:

In moving over the field, the wheel turning upon the ground, gives motion to the shaft, by means of which the seed is regularly delivered to the spouts. The earth-openers make a firm, deep furrow, in which the seed is deposited, and almost immediately hidden by the coverers.

The operator, holding the handles, has complete control of the machine. His position is such, also, that he can see the seed as it is deposited, and thus be sure that the machine is operating.

The markers lay off the ground for the next passage of the machine.

The hinged frame permits the wheel to pass over inequalities of surface, without affecting the main part of the machine.

Having thus fully described my invention,

What I claim, and desire to secure by Letters Patent of the United States, is—

1. The adjustable frame *E* *E*', constructed and arranged as described, with its shaft, wheel, and hoppers, in combination with the main frame *A* *B* *C* *D*.

2. The seed-planter described, consisting of the main frame *A* *B* *C* *D*, adjustable frame *E* *E*', with its attachments, earth-opener *B*', coverers *H*, and markers *J*, when combined and arranged as described, for the purpose set forth.

This specification signed and witnessed, this 18th day of September, 1868.

WILLARD H. SABINS.
